UNITED STATES PATENT OFFICE.

WILLIAM H. CLARK, OF ALBION, PENNSYLVANIA.

CASH INDICATOR AND REGISTER.

SPECIFICATION forming part of Letters Patent No. 433,888, dated August 5, 1890.

Application filed October 17, 1889. Serial No. 327,367. (No model.)

To all whom it may concern:

Be it known that I, WILLIAM H. CLARK, a citizen of the United States, residing at Albion, in the county of Erie and State of Pennsylvania, have invented certain new and useful Improvements in Cash Indicators and Registers; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention consists in the improvements in cash indicators and registers hereinafter set forth and explained, and illustrated in the accompanying drawings, in which—

Figure 1 is a perspective view of my improved cash indicator and register. Fig. 2 is a view of same in elevation with the front of the case removed and the base in section. Fig. 3 is a side elevation of same with the upper portion broken away and showing the door covering the dial mechanism open. Fig. 4 is a transverse section of same on the line 4-4 in Fig. 2, looking in the direction of the arrow. Fig. 5 is a detail view of a portion of the mechanism of the same.

Like letters refer to like parts in all the figures.

In the construction shown of my improved cash indicator and register B is the base of the case, and A the upright portion thereof. On the front of the upright portion A of the case is a circular indicator-plate C, secured at its ends a a' to the circular front of the portion A of the case, so as to leave a circular opening or groove b between it and the sides of the upright portion A of the case, suitable figures being placed on the front of the indicator-plate C, as and for the purpose hereinafter set forth. Through the portion A of the case is a transverse shaft D. To this shaft D is secured a gear-wheel d, which intermeshes with an elongated pinion E, mounted loosely on a stud-pin secured to the upper part of the left-hand side of the portion A of the case. On the end of the shaft D which extends through the right-hand side of the case A is also secured a hand or pointer

d', as and for the purpose hereinafter set forth. On a sleeve G, mounted loosely on the shaft D, is secured another large gear-wheel 55 F, having thereon eighty teeth and four carrying points or pawls f, adapted to consecutively engage with the loose pinion E, each of said pawls f moving said pinion E forward one tooth in passing it, which operates to rotate the gear-wheel d, intermeshing therewith, forward a like distance, as and for the purpose hereinafter set forth. A spring-dog e, secured to the frame, engages with the teeth of the pinion E, so as to prevent the 60 movement of the pinion E, except when actuated by the carrying-pawls f on the gear-wheel F. On the end of the sleeve G, secured to the gear-wheel d, extending through the right hand of the case A, is a hand or pointer 70 g, as and for the purpose hereinafter set forth. Mounted on the sleeve G on each side of the gear-wheel F are sleeves H H', to which are secured oscillating levers h h'.

Pivoted upon a rod I' is a semicircular rack 75 I, having inwardly-projecting teeth i thereon. To the lower portion J of the rack-bar I is secured a retracting-spring J', which operates to return the rack to its normal position, with the upper end K thereof resting against the 80 stop K'. On the oscillating arms N N' of the levers h h' are pivoted spring-actuated dogs k k', adapted to engage with the teeth of the gear-wheel F when the arms N N' of the levers h h' are raised so as to rotate the gear-wheel F, but to pass over the teeth of said gear-wheel when being moved downward, the dogs k k' being so arranged as to each operate on one-half of the faces of the teeth on the gear-wheel F, so as to pass each other 85 without interference, a spring-dog j, secured to the frame and engaging with the teeth of the gear-wheel F, preventing the backward movement thereof. The rear ends l l' of the levers h h' are beveled off in such shape 90 that the raising of the handles L L' of the levers h h', which project out through the grooves b at each side of the front of the case A, causes the ends l l' to pass downward over the teeth i of the rack I, with which they engage, so as to prevent the longer and heavier arms N N' thereof from falling down and returning to their normal position (as illustrated by the positions of the arms N N' and

handles L L' in Fig. 4) until released, as hereinafter set forth.

In the arms N N' of the oscillating levers h h' lateral stud-pins n n' are secured in such 5 position that when the arms N N' are at rest in their normal position, as illustrated by the position of the lever h in Fig. 4, the stud-pins n n' are under the end J² of the oscillating rack, as shown. Guards O O' are also secured to 10 the frame on each side of the wheel F in such position as to disengage the dogs k and k' from the teeth of the wheel F while the lever-arms N and N' are passing down to their normal positions, and until in raising them 15 the stud-pins n and n' pass out from under the ends J² of the rack I. In operation the levers h and h' are operated alternately, the raising of the arm N of the lever h operating to raise the end J² of the rack I up and throw 20 the end K thereof back, so as to release the end l' of the lever h' and permit the arm N' thereof to fall by gravity to its normal position, the stud-pin n' thereon during this operation passing under the end J² of the rack I 25 while it is being raised by the stud-pin n on the arm N of the lever H in its upward movement, and vice versa, the levers h and h' are operated alternately to actuate the wheel F and mechanism therewith connected and to 30 withdraw the rack I from the points l and l' of the levers, so that the raising of either one of the levers h and h' releases the other and allows it to fall to its normal position.

In the rear portion of the upright portion 35 A of the case is a vertically-sliding bar P, provided with a retracting-spring P', adapted to retain said bar in a normally-raised position. Across the lower end of said bar P and firmly secured thereto is a cross-bar P², which 40 extends out laterally into the boxes B², forming the base B of the case. The covers Q of the boxes B² are hinged thereto, so as to be raised up against the upright portion A of the case. These covers Q have lugs p' on the 45 under sides thereof, to which links p are pivoted, connecting them with the ends of the arm P², so that when the arm P² is raised it operates to simultaneously raise the covers Q, as illustrated by the dotted lines in Fig. 50 2. To the upper end K of the oscillating rack I is coupled a catch M, pivoted on the stud-pin m on the frame, the lower end m' of the catch M being adapted to engage with the upper end M' of the vertically-sliding bar P 55 when the same is down, as illustrated in Fig. 4, the operation of raising the oscillating levers h and h' and the throwing back of the upper end K of the rack I operating to release the catch M from the upper end M' 60 of the bar P, so that the retracting-spring P' raises it and throws open the covers Q Q, as illustrated by the dotted lines in Fig. 2, allowing access to the cash-receptacles covered thereby, after which the operator closes 65 the covers Q by hand, which operation forces the bar P down, so that the catch M engages

therewith and retains it in this position, locking the covers Q down in a closed position until one of the levers h or h' is again raised. To one side of the case is secured an 70 alarm-bell R, having an oscillating bell-hammer lever R', provided with a retracting-spring r. To the upper end of the bell-hammer lever R' is a spring-catch S, and on the back of the rack I, adjacent to the catch S, is 75 a hooked lug S', adapted to engage with the point of the catch S as the rack I is moved back by the raising of the lever h or h', carrying the end of the bell-hammer lever R' with it some little distance, when the lug S' slips 80 over the point of the catch S, releasing the lever R' and allowing the hammer to be forced quickly against the bell R by the retracting-spring r, so as to sound an alarm, the hooked catch S' passing over the dog S on 85 the return of the rack I to its normal position.

In operating my improved cash indicator and register the handle L or L' of one of the levers h or h' is raised so that the pointer 90 L² or L³ then points to the desired figures on the curved indicator-plate C, which operation permits the other handle L or L' to fall to its normal position ready for use, and also turns the gear-wheel F forward, 95 carrying the pointer g around on a dial T, marked with "cents," at the right-hand side of the case A, where it is retained by the spring-dog j, which operation of the handles L and L' is alternately repeated at each sale 100 until the hand g travels around the dial T, when at the next operation of the handle L or L' one of the carrying-pawls f engages with the loose pinion E, which moves the wheel d forward one notch, carrying the hand 105 d', secured to the shaft D thereon, forward one space over the dollar-dial T', surrounding the cents-dial T, each movement of the handles L and L' moving the hands g, and also periodically the hand d', and adding the 110 amount of the sale indicated to the aggregate indicated on the dials T T' by the hands g and d', and each operation of the handles L and L' also opens the covers Q of the cash-boxes, so that the cash can be deposited 115 therein. A door U, provided with a lock u, covers the dials T and T', so that they cannot be tampered with.

In setting the mechanism at zero it is only necessary to open the door U and turn the 120 hands g and d' around to o in the direction of their traverse.

Having thus fully described my invention, so as to enable others to construct and use the same, what I claim as new, and desire to secure by Letters Patent of the United States, is—

1. The combination, in a cash indicator and register, of a gear or ratchet wheel and an oscillating circular rack adjacent to said wheel, 125 with oscillating levers adapted to engage with the said rack, and dogs on said levers adapted

to engage with and actuate said gear or ratchet wheel, substantially as and for the purpose set forth.

2. The combination, in a cash indicator and register, of indicating and operating levers, and an oscillating curved rack adapted to engage such levers, with a gear or ratchet wheel adapted to be operated by dogs on said operating-levers, carrying-pawlson said wheel en-

10 gaging consecutively with and operating a loose pinion, a gear-wheel intermeshing with said loose pinion, and hands secured to the shaft of one and to a sleeve on the other of said wheels, substantially as and for the purpose set forth.

3. The combination, in a cash indicator and register, of curved indicator-plates secured to the machine-frame, oscillating levers having pointers passing over said plates and spring-
20 dogs thereon, with gear or ratchet wheels having carrying-pawls thereon and adapted to be actuated by the spring-dogs on said levers, and curved oscillating racks adapted to engage with the oscillating levers, substantially as and for the purpose set forth.

4. The combination, in a cash indicator and register, of the wheels F and d and the loose pinion E, intermeshing with the wheel d, the oscillating levers h h', having dogs k and k',
30 adapted to engage the teeth in the wheel F, with the oscillating rack I, and the stud-pins n and n' on the arms N and N' of the levers h and h', substantially as and for the purpose set forth.

35 5. The combination, in a cash indicator and register, of an oscillating rack I and the catch M, coupled thereto, with the vertically-sliding bar P, having a retracting-spring P' and the

cross-bar P² thereon, the hinged covers Q Q, and the link p, connecting said hinged covers 40 with the ends of the cross-bar P², substantially as and for the purpose set forth.

6. The combination, in a cash indicator and register, of a curved oscillating rack I, having a lug S' thereon, and the oscillating levers h h', 45 with the bell-hammer mechanism R' S and the alarm-bell R, substantially as and for the purpose set forth.

7. The combination, in a cash indicator and register, of a gear-wheel d, intermeshing with 50 a loose pinion E, having a spring-dog e operating thereon, and a gear or ratchet wheel F, secured to a sleeve G, mounted upon the shaft of the wheel d, carrying points or pawls f, secured to the wheel F and adapted to engage 55 with and turn the loose pinion E, a spring-dog j, operating to prevent the backward movement of the wheel F, a hand d', secured to one end of a shaft of the wheel d, and a hand g, secured to the end of the sleeve G, 60 which hands travel over dials T and T', with rocking levers h and h', having dogs k and k' thereon adapted to engage with the teeth of the wheel F, and having stud-pins n and n' thereon, and an oscillating rack I, adapted to 65 engage with the rear ends l l' and also with the stud-pins n and n' of the oscillating levers h h', substantially as and for the purpose set forth.

In testimony whereof I affix my signature in 70 presence of two witnesses.

WILLIAM H. CLARK.
